UNITED STATES PATENT OFFICE.

RICHARD PALMER, OF SOUTH ALBURG, VERMONT.

RAIL TIE.

Application filed April 17, 1922, Serial No. 553,563. Renewed March 5, 1923.

To all whom it may concern:

Be it known that I, RICHARD PALMER, a subject of the King of England, residing at South Alburg, in the county of Grand Isle 5 and State of Vermont, have invented certain new and useful Improvements in Rail Ties; and I do declare the following to be a full, clear, and exact description of the invention, such as will enable others skilled 10 in the art to which it appertains to make and use the same.

This invention relates to an improved rail tie, and it has for its principal object to generally improve upon devices of this class 15 by providing one of extreme simplicity and durability which comprises a connecting bar or tie provided on its under face and near its opposite ends and directly beneath the rails with a yieldable cushioning means 20 which serves to relieve the rails from violent shocks and jars to which they are subjected, thereby decidedly increasing their life.

More specifically speaking, it is another object of the invention to provide a tie which 25 is formed at its opposite ends with pockets in which a resilient substance is placed, the tie proper resting directly on this substance which is intended to yield sufficiently to absorb the shocks to which the rails are subjected when a train of cars is passing there- 30 over.

Other objects and advantages of the invention will be apparent during the course of the following description.

35 In the accompanying drawings forming a part of this specification and in which like numerals are employed to designate like parts throughout the same;

Figure 1 is a central longitudinal sectional view through a rail tie constructed in accordance with this invention, and showing the same in use.

Figure 2 is a side elevation view thereof.

Figure 3 is a bottom plan view of one of 45 the cushioning members.

Figure 4 is a transverse vertical section taken on the line 4—4 of Figure 1.

In the drawing, the reference character 1 50 designates a cross-tie, across which the rails R extend at right angles, the same being secured in place by fastening members held in place by lag screws which are in turn anchored and held against movement by means to be hereinafter described.

55 As hereinbefore mentioned, it is desirable in carrying out the invention to provide

means for co-operation with the underface of the tie adjacent the opposite ends thereof for absorbing shocks and jars to which the rails are subjected. Although the means could be of some other construction, it comprises what may be conveniently termed, a pair of pockets formed at the opposite ends by a pair of substantially U-shaped resilient metal straps 2 which have their opposite 60 ends bent to extend in parallelism with the tie and formed with slots 3 slidably engaged with bolts 4 extending vertically through the tie. With this arrangement, the ends of the straps are permitted to move in 65 a manner to permit the filler 5 in the pocket to become effective in absorbing the shocks. Although the filler could be of any other substance or material, it is preferably composed of evaporated tar mixed with sand 70 and saw-dust to render it sufficiently rigid to serve for effectively accomplishing the ends sought. The tie directly bears on the 75 filler so that the shocks are directly taken up by the latter. By preference, short anchoring blocks 6 are embedded in the tar and these are formed with sockets into which the lower ends of the aforesaid screws are received to hold the latter against misplacement. For the purpose of confining the 80 filler in the pocket, I prefer to use side plates 7, these being connected with the vertical sides of the tie in a manner to permit relative movement of the latter with respect to the plates. As shown, the plates are formed 85 with elongated slots 8 and fastening bolts 9 pass through these slots and into the tie and the latter is permitted to have a free relative movement with respect to the plates. 90

If desired, additional fastenings 10 may be 95 passed through the plates and through the filling material 5 to assist in holding the plates in position. It may be pointed out here, that the plates 7 are normally spaced 100 away from the tie, but are capable of being moved toward it upon tightening the nuts on the ends of the bolts 10 to slightly contract the filling material and render it more rigid.

From the foregoing description it is clearly apparent that when the rails are subjected to shocks by a passing train, the filling material 5 will serve as a shock absorbing medium and due to the fact that the ends of the plates 2, which form the pockets 105 have slidable connection at their ends with the tie, they will compensate for the down-

- ward movement of the latter. This movement will not be interfered with by the plates 7 as these have a slidable connection with the tie so as to permit relative movement of the same with respect to the confining plate. I desire to point out that the filling material in practice must be such as to prevent it from freezing in cold weather or melting in extremely warm weather, and although I have specified a certain kind of material for use, I wish it to be understood that any other kind of suitable material may be employed. As a matter of fact, a wooden block may suffice as a substitute for the resilient filling material. It is of course understood that when a tie is in use, the pockets, side plates, and the filling material will be embodied in the ground to anchor the tie and prevent slippage thereof.
- 20 By carefully considering the foregoing description, in connection with the drawings, persons familiar with devices of this class will doubtless be able to obtain a clear understanding of the invention.
- 25 Therefore, a more detailed description is deemed unnecessary.
- Since probably the best results may be obtained with the construction and arrangement herein shown and described, this is taken as the preferred embodiment of the invention. However, I wish it understood that minor changes coming within the scope of the inventions as claimed may be resorted to if desired.
- 30
- 35 I claim:—
1. In combination, a rail tie, strips of resilient material connected at their outer ends to the underface of the tie near the opposite ends of the latter, said strips forming pock-
- ets, a quantity of yieldable material arranged in said pockets, the tie resting directly on said material.
2. A rail tie cushioning means comprising a substantially U-shaped resilient metal strap designed to have its opposite ends slidably connected with the under side of the tie, said strap serving to form a pocket, a quantity of yieldable material designed to be placed in said pocket, and means embedded in said material to permit connection of fastening screws for the ties therewith.
3. The structure set forth in claim 2, together with a pair of side plates for confining the material in said pockets, said side plates being designed to have slidable connection with the tie so as to permit relative movement of the latter with respect thereto.
4. In combination, a rail tie, a pair of substantially U-shaped resilient strips of metal having their free ends contacting the under-side of said tie and formed with slots, fastening means passing through the tie, said slots slidably engaging with such fastenings, said strips forming pockets, resilient filling material arranged in said pockets, blocks embedded in said material with which the lower end of the rail fastening bolts are connected, side plates for confining the material in said pockets, said side plates being formed at the upper edge with vertical slots, and bolts passing through said slots and connected with the tie to permit relative movement of the latter with respect to said side plates.

In testimony whereof I have hereunto set my hand.

RICHARD PALMER.
